RECIPROCAL ACTUATED ROTATING SPINNER GAME DEVICE

Filed Feb. 21, 1949

BY
Howard L. Johnson
ATTORNEY

scoring ring 16 are allotted to 18 positions corresponding to the number of holes in golf, plus 6 "hazards" and 4 "tees" or starting positions, one for each player or operating rod 26, 40. In an inner circle are numbers corresponding to "par strokes" for the 18 holes and "penalty strokes" for the hazards. Accordingly, each player in turn places the ball 22 on his tee and tries to land it on the No. 1 position with three strokes. If he accomplishes this in three or less, he records the number of strokes and the next player takes his turn and does likewise. If the par number of three strokes are used up without landing the ball on the No. 1 position, the turn then passes to the next player, and upon its return to the first player he again has three strokes to land the ball on No. 1. If a player gets to the desired position in less than par, he records this smaller number and the next player takes his turn. When the play returns to the first player, he then tries to land the ball on the No. 2 position in the par number of strokes for this hole and so on. If a player's ball stops on a "hazard" he adds the appurtenant number of penalty strokes to his score. If the ball comes to rest on a tee, he merely plays the shot over. Of course other methods of scoring may be used and other symbols may be placed around the scoring ring.

While I have shown and described in some detail, presently preferred embodiments of my table game device, it is to be understood that various modifications may be made in the construction and operation thereof within the spirit and scope of the subsequently claimed invention which it is my intention to define broadly within the limitations imposed by the prior art.

This is a continuation-in-part of my application for a Game Device, Serial No. 788,596, filed Nov. 28, 1947, and issued as U. S. Patent 2,462,507, February 22, 1949.

I claim:

1. A game device comprising: a surface bearing scoring indicia arranged in an annular path and having playing positions spaced about the periphery thereof; a radial arm extending toward said path from the center thereof and mounted for pivotal movement about said center, said arm having an offset portion projecting beneath said surface; a plurality of reciprocable, outwardly projecting rods located beneath said surface and extending to individual playing positions, each rod having a contact portion at its inner end adapted for selective momentary engagement with the offset portion so as to propel the radial arm about said path; and a guideway beneath said surface for each rod whereby a player at the appurtenant playing position may establish striking contact between said offset portion and the contact portion upon moving the latter to its innermost position in the guideway.

2. A game device comprising: a surface bearing scoring indicia arranged in an annular path; a radial arm extending toward said path from the center thereof and mounted for pivotal movement about said center, said arm having an offset portion projecting beneath said surface; a reciprocable, outwardly projecting rod located beneath said surface and having a contact portion at its inner end adapted for momentary engagement with the offset portion so as to propel the radial arm about said path; and a guideway for said rod beneath said surface wherein a player may reciprocate the same to engage and disengage it with said offset portion.

3. A game device comprising: a surface bear-

ing scoring indicia arranged in an annular path; a radial arm extending toward said path from the center thereof and mounted for pivotal movement about said center, said arm having an offset portion projecting beneath said surface; a reciprocable, outwardly projecting rod located beneath said surface and having a contact portion at its inner end adapted for momentary engagement with the offset portion so as to propel the radial portion about said path; a guideway for said rod beneath said surface wherein a player may reciprocate the same to engage and disengage it with said offset portion; and resilient means for normally holding the rod in disengaged position.

4. In a game device of the character described including a surface bearing scoring indicia arranged in an annular path and a radial arm extending toward said path from the center thereof and mounted for pivotal movement about the center, said arm having an offset portion projecting beneath said surface, the improvement comprising: a reciprocable and rotatable operating rod disposed beneath said surface in a guideway extending outward from the center thereof and having a contact portion at its inner end adapted for momentary engagement with said offset portion so as to propel the radial arm about said path; resilient means for normally holding the rod in disengaged position; and a guide element having a contact edge disposed angularly to the axis of said rod for sliding engagement with the contact portion thereof, whereby rotation of the rod in contact with said edge causes it to be moved longitudinally to or from a position wherein said contact edge is disposed for striking engagement with the offset portion.

5. In a game device of the character described including a surface bearing scoring indicia arranged in an annular path and a radial arm extending toward said path from the center thereof and mounted for pivotal movement about the center, said arm having an offset portion projecting beneath said surface, the improvement comprising: a reciprocable, pivoted operating rod disposed beneath said surface, extending outward from the center thereof, and having a contact portion at its inner end adapted for momentary engagement with said offset portion so as to propel the radial arm about said path; a pivot pin disposed in a longitudinal slot in said rod whereby the rod may be reciprocated between engaged and disengaged positions and also swung on said pin to strike said offset portion; and resilient means for normally holding the rod in disengaged position.

SOREN M. KLYVER.
